UNITED STATES PATENT OFFICE

1,989,204

TRANSPARENT STARTING BOX

Hattie S. Levenson, Miami, Fla.

Application December 15, 1932, Serial No. 647,455

1 Claim. (Cl. 119—15.5)

The invention forming the subject matter of this application relates to improvements in starting boxes used in dog racing to hold dogs preparatory to starting a race.

5 The boxes used heretofore are usually constructed to provide a separate compartment for each dog; and ordinarily are provided with doors designed to operate so as to effect the simultaneous release of all the dogs in a box.

10 Heretofore, it has been customary to make these boxes of opaque material, so that when the dogs were locked in their compartments, it was impossible for the owners, or for the public interested, to determine whether or not the dogs 15 were properly positioned in their compartments, or that their identifying numbers had not been changed by unscrupulous starters. The compartments in these boxes are always constructed so that the dogs cannot turn around in them, 20 and dogs have sometimes been deliberately placed therein with their heads turned toward the rear instead of the front of the box.

It is, therefore, the main object of the present 25 invention to provide a starting box divided into compartments, and in which the ends, top and partitions, at least, are made of transparent material.

In race tracks such as are shown in the U. S. 30 Patent No. 1,850,040, it is customary to arrange the starting boxes across the course between the barrier walls enclosing the course. As soon as the dogs are started it is necessary to remove the starting box as quickly as possible from the course; otherwise, the dogs in completing a lap 35 would find the course obstructed by the box. Since these boxes are usually heavy and cumbersome, they are hard to maneuver and remove in the short time the dogs consume in running a lap. It is therefore another object of this invention to provide each starting box with a supporting base, adapted to be positioned adjacent a gap made in the track barrier, along which the box may be readily moved into and out of starting position on the course.

40 Still another object of the invention is to provide a box of this character in which all the doors at the front of the box are snapped simultaneously to effect simultaneous release of the dogs in a box.

45 Other objects of the invention will become apparent as the detailed description thereof proceeds.

In the drawings:

50 Figure 1 is a perspective view of the starting box;

Figure 2 is a vertical transverse section taken on the line 2—2 of Figure 1;

Figure 3 is a fragmentary end elevation of part of the back of the starting box;

Figure 4 is a fragmentary transverse section taken on the line 4—4 of Figure 2;

Figure 5 is a fragmentary elevation of a pair of doors in the front of the starting box;

Figure 6 is a fragmentary perspective view of a modified form of the invention; 10

Figure 7 is a detail to an enlarged scale of locking mechanism used in the modification shown in Figure 6; and

Figure 8 is a fragmentary diagrammatic plan view of starting boxes as applied to the course of 15 dog race track.

In racing apparatus of the character illustrated in U. S. Patent No. 1,850,040, it is customary to arrange a starting box 1 (see Figure 8) across the course 2, along which a lure 3 is 20 adapted to be moved at various speeds by mechanism well known in this art, and shown for example in the aforesaid patent. It is usual to arrange several of these boxes at various distances around the track in accordance with 25 the distances of the several races to be run. For example, the boxes 4 and 5 may be arranged at various distances from the box 1, where it is found desirable to vary the distance run.

For distances greater than the length of the 30 course, it is necessary to remove the boxes from the track, to clear the track of obstruction for the dogs after they have completed the circuit from the starting point and are required to continue the race for additional laps. It is also necessary to move these boxes very quickly because 35

the dogs run very fast and complete the circuit, usually about one quarter mile around, in a matter of about twenty-five seconds. It therefore becomes important to provide means whereby 40

the starting boxes may be quickly withdrawn from the course. For this purpose, the boxes of the present invention are mounted to slide on base members 6, outside the track and is provided with parallel channel runways 7 and 8 adapted 45

to receive slidably the rails 9 and 10, suitably secured to the bottom 11 of the starting box 1. The bottom 11 projects at the other end of the starting box beyond the end wall thereof. This 50 projection 12 is intended to keep the rails 9 and 10 positioned in the track 7 and 8 when the starting box is arranged in the track, as shown in Figure 8; thereby avoiding the necessity of the operator having to lift one end of the box bodily from the track, in order to posi-

tion it in the channel members 7 and 8. The base member 6 is provided with a stop 13 at its outer end, to limit the movement of the starting box 1 outwardly from the track. Preferably, the 5 stop is positioned so that the inner end wall 14 of the starting box will lie substantially flush with the wall 10' of the track when the box is removed from the course 2. So far as this particular 10 mount for the starting box is concerned, it is 10 immaterial just how the box itself is constructed. However, it is preferred that it be constructed substantially as shown in Figures 1 and 6 of the drawings.

In the form of the invention illustrated in Figure 15 1, the end walls 14 and 15 are made of transparent material. The top 16 is also made of transparent material, such as glass. The back of the starting box comprises a panel 17 of glass or other transparent material; and the starting box 20 as a whole is divided into a plurality of compartments by partitions 18, which are also made of transparent material.

Entrance to the compartment is effected through doors 19 which may or may not be transparent, but preferably are transparent. It will of course be understood that in constructing the various walls and partitions of transparent material, suitable framework will be provided so that these parts may be properly connected together. 30 It is immaterial whether this framework be made of wood or metal. The essential thing is that substantially all of the top, the end walls and the partitions shall be transparent. Entrance into the various compartments is effected through the doors 19, which are suitably hinged to the aforesaid framework and are provided with manually operable latches 20. The front part of the box 1 comprises an upper panel 21 which is preferably transparent. The front panel 21 has a holding bar 22 hinged to the lower rail 23. The bar 22 is adapted to swing by gravity against the upper rails of the doors 24, preferably made of glass panels suitably secured in frames 25.

Each compartment 16 has its front end closed 45 by a pair of doors 24; the doors 24 are hinged to upright rails 26, which form part of the framework in which the transparent panels of the partitions 18 are suitably secured.

To effect the simultaneous opening of all the 50 doors, a pair of bars 27 and 28 are hinged to the swinging edges of the doors to effect the simultaneous opening of the doors when released from the weight of the bar 22. The bar 27 extends across the face of all the doors 24 and is connected by hinges 29 to the swinging edges of the right hand doors 24 by means of the hinges 30. The bar 28 extends across the face of all the doors 24 and is connected by hinges 31 to the swinging edges of the left hand doors 24. It is obvious 55 from this construction that if a bar 27 be pulled outwardly from the front of the box 1, it will open all of the right hand doors 24 simultaneously. It will also be obvious that when the bar 28 is pulled outwardly, it will open all the left hand 60 doors of the box simultaneously.

To effect the simultaneous opening of all the doors, the framework of the end walls 14 and 15 has suitably secured thereto, the rods 32 and 33 which project for some distance beyond the 70 front face of the box 1. A tension spring 34 is connected at one end to a hook 35 in the outer end of the rod 32, and at its other end is connected to an eyelet or hook 36 suitably secured to the bar 28 near the center thereof. Similarly, a tension spring 37 is connected to a hook 38 in

the outer end of the rod 33 while its inner end is connected to a hook 39 substantially in the center of the bar 27.

It will be apparent from Figure 1 of the drawings that the tension springs 34 and 37 would normally hold all of the doors 24 in open position. However, it is intended that the doors will be closed by means of a heavy bar 22. When it is desired to open the doors 24, the bar 22 may be swung upwardly about its hinged connection with the rail 23 to release the top of the doors 24 from its holding effect, thereby permitting the springs 34 and 37 to snap all of the doors simultaneously into open position. It will be understood, of course, that rubber cables, or any other suitable resilient material or weights, may be substituted for the tension springs.

In the form of the invention illustrated in Figure 6, the doors 24 and the framework in general is the same as illustrated in Figures 1 and 2. In this case, however, the door holding means is somewhat different. The bar 22 of Figures 1 and 2 is replaced by a shaft 40 which is journaled in bearing brackets 41 and 42 suitably secured at opposite ends of the framework of the starting box front wall. In this modification, the doors 24 and bars 27 and 28 are similar to those illustrated in Figures 1 and 2. The shaft 40 is provided with laterally extending fingers 41' which are of sufficient length to extend across both of the bars 27 and 28 for the purpose of holding all of the doors 24 closed by pressure exerted upon the aforesaid bars 27 and 28.

The shaft 40 projects beyond its bearing bracket 42 and has a rod 43 extending diametrically therethrough. The lower end of the rod 43 projects into the path of movement of a latch lever 44 which is suitably pivoted to a bracket 44' secured to the rod 33. The latch lever 44 is provided with a weight 45 at the side of the pivot 46 opposite to the hook end of the aforesaid latch. A stop 47 limits the downward movement of the latch 44. The upper end of the rod 43 has one end of a tension spring 48 secured thereto. The other end of said spring 48 is fixed to the framework at the back of the starting box.

It will be obvious from inspection of Figures 6 and 7 that when the latch 44 is in the position shown in Figure 7 of the drawings, the shaft 40 will be so disposed that all the fingers 41 press against the bars 27 and 28, thereby holding all the doors 24 in closed position. When it becomes necessary to release the doors from the starting box, the operator merely trips or raises the weighted end 45 of the latch 44, thereby releasing the rod 43. Upon release of this rod 43, it is obvious that the tension spring 48 will rotate the shaft 40 to swing the fingers 41 away from the bars 27 and 28, thereby permitting the tension springs 34 and 37 to snap all of the doors 24 open simultaneously.

To avoid accidental movement of the starting box along its base into the course, the base and the bottom of the box are provided with any suitable form of friction locking means such as the common ball and socket latch 12' and 13' shown in the drawings. Any other suitable form of latch may be used for this purpose.

The invention is not to be considered as limited to the use of front doors in pairs. It is contemplated that a single door may be substituted for each pair of front doors, and that any other well known means may be substituted for the transverse bars 27 and 28 to open all the doors simultaneously.

It is obvious that many minor changes may be made in the form and construction of the invention without departing from the principles thereof. It is not, therefore, desired to confine the invention to the exact form herein shown and described but it is desired to include all forms properly coming within the scope claimed.

5 What I claim is:

A starting box for dogs, comprising a skeleton frame, top and side walls of smooth and imper-

forate transparent material, such as glass, a plurality of spaced partition members also of smooth and imperforate transparent material defining stalls, said top, side walls and partition members being mounted in said frame, a plurality of transparent doors hinged to said frame, and means supported by said frame connected to the doors for swinging of said doors to open position.
